US0D1006821S

(12) **United States Design Patent** (10) **Patent No.:** **US D1,006,821 S**
Putnam et al. (45) **Date of Patent:** **** Dec. 5, 2023**

(54) **DISPLAY SCREEN OR PORTION THEREOF WITH GRAPHICAL USER INTERFACE**

(71) Applicant: **Curiouser Products Inc.**, New York, NY (US)

(72) Inventors: **Brynn Putnam**, New York, NY (US); **Kevin Twohy**, Brooklyn, NY (US); **Jonathan Self**, Brooklyn, NY (US)

(73) Assignee: **Curiouser Products Inc.**, New York, NY (US)

(**) Term: **15 Years**

(21) Appl. No.: **29/704,708**

(22) Filed: **Sep. 6, 2019**

Related U.S. Application Data

(63) Continuation-in-part of application No. PCT/US2019/034292, filed on May 29, 2019.

(51) **LOC (14) Cl.** **14-04**

(52) **U.S. Cl.** **USPC .....** **D14/485**

(57) **CLAIM**

The ornamental design for a display screen or portion thereof with graphical user interface, as shown and described.

DESCRIPTION

The FIGURE is a front view of a display screen or portion thereof with graphical user interface showing our new design.

The outermost dashed broken lines in the FIGURE show a display screen or portion thereof and form no part of the claimed design. The remaining broken lines show portions of the graphical user interface that form no part of the claimed design.

1 Claim, 1 Drawing Sheet
